EBENEZER HILL, OF SOUTH NORWALK, CONNECTICUT, ASSIGNOR TO THE HILL COMPRESSOR & PUMP COMPANY, OF NEW YORK, N. Y., A CORPORATION OF DELAWARE.

ROTARY COMPRESSOR.

Application filed October 26, 1923. Serial No. 670,898.

To all whom it may concern:

Be it known that I, EBENEZER HILL, a citizen of the United States, residing at South Norwalk, in the county of Fairfield 5 and State of Connecticut, have invented a new and useful Improvement in Rotary Compressors, of which the following is a specification.

This invention relates to motor driven rotary fluid compressors of the type in which there is a rotor connected with and driven by the armature shaft of an electric motor, which rotor contains and actuates two intermeshing pumping gears that are 10 held in engagement with a wall of the pumping chamber so that the fluid being pumped will not leak across the faces of the gears, primarily, as on starting, by a light spring, but when in operation, by the excess 15 discharge pressure of the fluid pumped exerted against the back of the rotor. In compressors of this character when there is merely atmospheric pressure on both the intake and discharge sides, the rotor is held against the 20 wall of the pumping chamber by the tension of the spring back of the rotor, with only sufficient force to cause slight frictional engagement, so that the motor starts the compressor easily. As the discharge pressure 25 builds up under the action of the compressor, the force on the back of the rotor increases and the sealing engagement of the rotor and gears with the wall of the pumping chamber is correspondingly increased. When 30 the compressor is working the pressure on the opposite sides of the rotor is to an extent balanced there being little more pressure on the back than the front, but this is not excessive and therefore the friction is 35 not great and the motor drives the compressor easily.

When such a compressor is stopped with pressure on the discharge side that pressure remains exerted against the back of the 40 rotor, but on the front the pressure tends to leak across the faces of the gears until the pressure on that side is reduced to approximately the intake pressure, which ordinarily is atmospheric pressure. Under such a condition the pressure on the back tends to hold the rotor and gears very forcibly against the 45 wall of the pumping chamber, and in order to again start up the compressor the motor must have a very great starting torque and 50 be able to stand considerable overload. But

as soon as the compressor starts and begins to pump the pressure on the front of the rotor increases to nearly that on the back, and the frictional engagement of the rotor and gears with the wall of the pumping 60 chamber being thus reduced the motor runs with its normal friction load. These factors make necessary the employment of a relatively large sized motor and one that is especially built so as to have a high starting 65 torque, which will overcome the initial frictional load when the compressor is stopped under pressure.

The object of the present invention is to provide equalizing means preferably located on the intake side of the compressor, which will remain inactive when the pressure is atmospheric on both sides, or is practically balanced on both sides of the rotor, as when the compressor is working, but will, if the 70 compressor is stopped with a high pressure on the discharge side, act to retain the pressure on the intake side at substantially the same degree as on the discharge side, in order that the only friction of the rotor 75 and gears against the wall of the pumping chamber will be that due to the action of the spring. With the pressure thus in effect balanced, the motor will start the compressor easily and without overload. As a 80 result of the use of this equalizing means a smaller and less expensive motor, with a standard starting torque, can be used, than is required when the compressor is not provided with equalizing means. This effects a 85 considerable saving in the initial cost of the apparatus and an economy in running expense.

This object is attained by arranging a valve on the intake side of the compressor, 90 desirably in the intake port in the head, in such manner that it offers no practical obstruction to the flow of fluid under the normal operation of the compressor, but when the compressor is stopped with high 95 pressure on the discharge side, and the fluid tends to leak back across the faces of the pumping gears, that leakage will cause the valve to close the intake port and retain the fluid pressure on the intake side or front 100 faces of the rotor and gears substantially the same as on the discharge side or back face of the rotor, thus reducing the friction so that the compressor will again start without 105 excess resistance to torque. The equalizing 110

means also acts to automatically check the flow of lubricant into the pumping chamber when the compressor is stopped with pressure on the discharge side.

5 In the accompanying drawings Figure 1 shows a side view of a motor driven compressor of the character referred to, with a portion of the compressor cut in longitudinal section to disclose an equalizing means 10 arranged in the intake port or the head. Fig. 2 is a transverse section of the compressor on the plane indicated by the dotted line 2—2 on Fig. 1. Fig. 3 is a transverse section on the plane indicated by the dotted line 3—3 on Fig. 1.

The casing 1 which is generally circular in outline contains a cylindrical pumping chamber 2 that is closed at one end by a head 3 which is fastened to the casing by 20 any suitable means. The casing has an intake passage 4 on one side and a discharge passage 5 on the other side, while the head has an intake port 6 leading from the intake passage to the pumping chamber and a discharge port 7 leading from the pumping chamber to the discharge passage. Rotatably fitting and having a slight movement axially in the pumping chamber is a rotor 8. The hub 9 of the rotor is mounted on anti- 30 friction bearings 10 the inner ring 11 of which is fastened to the hub while the outer race ring 12 is fitted so that it may have a slight axial movement in the casing. The driving shaft 13 is splined in the hub of the 35 rotor so that while the shaft will turn the rotor it will not interfere with the axial movement of the rotor. Fastened in the rotor is an internally toothed gear 14 and engaging the teeth of this gear are the teeth of 40 an externally toothed gear 15. The externally toothed gear is mounted on anti-friction bearings 16 arranged in a cavity 17 in the gear and supported by a stud 18 fastened in the head. The stud is positioned out of 45 line with the driving shaft so that the axis of the externally toothed gear will be eccentric with the axis of the internally toothed gear. One of these gears has more teeth than the other and they coat in a well 50 known manner to effect the pumping or compression of fluids.

A spring 19 is arranged in a cavity 20 that communicates with the pumping chamber, in such manner that it thrusts against 55 the outer race ring 12 and through the bearing presses the rotor and the faces of the pumping gears against the inner face of the head. Lubricant is introduced into this cavity. Leading from the reservoir 21 into 60 which the fluid is pumped, to the cavity containing the spring is a pipe 22. The function of this connection is to admit discharge pressure to the cavity and permit it to be exerted on the back of the rotor. This connection also is adapted to conduct back lubri-

cant which has been forced through the joints of the pump and out through the discharge pipe. A common type of gland packing 23 is arranged in the end of the casing to prevent leakage from the spring 70 cavity around the driving shaft.

A duct or passage 24 is made through the hub of the rotor from the pressure cavity containing the spring back of the rotor, to the cavity containing the bearing for the externally toothed gear in front of the rotor. When the pump is running the centrifugal force of the externally toothed gear and the fact that it wipes around on the face of the head is sufficient to allow just the right 80 amount of lubricant to work out on the faces of the gears and also between the contacting faces of the teeth. The lubricant which escapes passes through the discharge and is returned to the pressure chamber so as to 85 furnish a continuous supply of lubricant under pressure.

In the apparatus illustrated the armature shaft of the electric motor 25 is directly connected with and acts as the driving shaft for 90 the rotor of the compressor. In order to accomplish the object of this invention and enable the motor to start without excessive torque and overload, in the apparatus shown, a valve 26 is located in the head and is 95 pressed by a light spring 27 so as to normally close the intake port. This valve and spring are located in a screw plug 28 threaded into the head opposite the intake port. The valve however could be placed at any 100 convenient locality on the intake side of the compressor.

When the compressor is started up and as it continues to run, the inrushing fluid to the pumping chamber overcomes the light 105 tension of the spring and holds the equalizing valve open. As there are no pulsations in the compressor and the inrush of air is substantially steady the equalizing valve has no vibration. However when the compressor is stopped with fluid pressure on the discharge side, the equalizing valve is closed by its spring because there is no entering 110 fluid to hold it open. Immediately this valve closes the pressure that leaks back across the 115 faces of the gear teeth from the discharge cavities into the intake cavities, as it cannot get past the equalizing valve, it builds up until the pressure on both sides of the rotor becomes equal. With the pressure balanced 120 the only force tending to hold the rotor and gears against the face of the head is that of the spring in the cavity back of the rotor, and this being relatively light the frictional resistance of the rotor and gears to the motor on starting will be the same as if there was atmospheric pressure on both the intake and discharge sides of the compressor. With this arrangement there is an advantage in 125 permitting a slight amount of leakage across 130

the face of the gears. If the compressor is to start up and shortly stop, and then soon start up again, automatically on a fluctuating cycle of pressure which requires it to 5 start and stop quickly at various intervals, the amount of leakage could be increased somewhat, so that the pressure due to the closing of the intake by the equalizing valve would act promptly and the stabilizing of 10 the pressure on the rotor be quickly effected, in order that the motor be in condition to start at any time without excessive overload.

This pressure equalizing valve in the inlet 15 has another advantageous function. Besides equalizing the pressure and allowing the motor to start without a high starting torque, it ensures the same pressure at both ends of the lubricating port through the rotor.

20 This stops the lubricant flow as there is no excess pressure on the back to force it through the port on account of the pressure being the same on both sides, and the rotation having ceased, there is no wiping effect of the gears to pass this lubricant along. Therefore in addition to making the starting torque lighter the supply of lubricant is automatically stopped and started with the compressor by the equalizing means.

25 The invention claimed is:—

1. A rotary compressor comprising a casting containing a pumping chamber with an intake to and a discharge from said chamber, a rotor rotatable in and having an

30 axial movement in said chamber, intermeshing internal and external pumping gears rotated by and having an axial movement with said rotor, means for conducting discharge pressure to the back of the rotor for forcing the rotor and gears toward the front end of the pumping chamber, and means on the intake side permitting an unrestricted flow of fluid to the front of the pumping chamber but preventing the escape of fluid back from the pumping chamber so as to keep the pressure on the front of the rotor substantially the same as the discharge pressure on the back of the rotor when the compressor is idle and thereby lower the starting torque of the compressor.

35 40 45 50

lower the starting torque of the compressor.

2. A rotary compressor comprising a casting containing a pumping chamber, a head closing the front end of the pumping chamber, said head having an intake to and a

55 discharge from said chamber, a rotor rotatable in and having an axial movement in said chamber toward and from the head, intermeshing internal and external pumping gears rotated by and having an axial

60 movement with said rotor, means for conducting discharge pressure to the back of the rotor for forcing the rotor and gears toward the head, and means on the intake side permitting an unrestricted flow of fluid to the front of the pumping chamber but preventing the es-

70 preventing the escape of fluid back from the pumping chamber so as to keep the pressure on the front of the rotor substantially the same as the discharge pressure on the back of the rotor when the compressor is idle and thereby lower the starting torque of the compressor.

3. A rotary compressor comprising a casting containing a pumping chamber with an intake to and a discharge from said chamber and a cavity communicating with the back of the chamber, a rotor rotatable in and having an axial movement in said chamber, intermeshing internal and external pumping gears rotated by and having an axial movement with said rotor, a spring in the cavity adapted to force the rotor and gears toward the front of the pumping chamber, means for conducting discharge pressure to the back of the rotor for, with said spring, forcing the rotor and gears toward the front of the pumping chamber, and means on the intake side permitting an unrestricted flow of fluid to the front of the pumping chamber but preventing the escape of fluid back from the pumping chamber so as to keep the fluid pressure on the front of the rotor substantially the same as the fluid pressure on the back of the rotor when the compressor is idle and thereby lower the starting torque of the compressor.

35 40 45 50 55 60 65 70 75 80 85 90 95 100 105 110 115 120 125 130

4. A rotary compressor comprising a casting containing a pumping chamber with an intake to and a discharge from said chamber, a rotor rotatable in and having an axial movement in said chamber, an electric motor directly connected with and adapted to drive the rotor, intermeshing internal and external pumping gears rotated by and having an axial movement with said rotor, means for conducting discharge pressure to the back of the rotor for forcing the rotor and gears toward the front end of the pumping chamber, and means on the intake side permitting an unrestricted flow of fluid to the pumping chamber but preventing the escape of fluid back from the pumping chamber so as to keep the pressure on the front of the rotor substantially the same as on the back of the rotor when the compressor is idle and thereby lower the starting torque of the compressor.

5. A rotary compressor comprising a casting containing a pumping chamber with an intake to and a discharge from said chamber, intermeshing internal and external pumping gears rotated in and having an axial movement in said chamber, means for conducting discharge pressure to the back of the gears for forcing the gears toward the front end of the pumping chamber, and means on the intake side permitting an unrestricted flow of fluid to the front of the pumping chamber but preventing the es-

5 cape of fluid back from the pumping chamber so as to keep the pressure on the front of the gears substantially the same as the discharge pressure on the back of the gears when the compressor is idle and thereby lower the starting torque of the compressor.

6. A rotary compressor comprising a casting containing a pumping chamber, a head closing the front end of the pumping chamber, said head having an intake to and a discharge from said chamber, a rotor rotatable in and having an axial movement in said chamber toward and from the head, intermeshing internal and external pumping 10 gears rotated by and having an axial movement with said rotor, means for conducting discharge pressure to the back of the rotor for forcing the rotor and gears toward the head, and a valve in said head on the intake 15 side permitting an unrestricted flow of fluid to the front of the pumping chamber but preventing the escape of fluid back from the pumping chamber so as to keep the pressure on the front of the rotor substantially the same as the discharge pressure on the back of the rotor when the compressor is idle and thereby lower the starting torque of the compressor.

7. A rotary compressor comprising a casting containing a pumping chamber with an intake to and a discharge from said chamber, a rotor rotatable in and having an axial movement in said chamber, intermeshing internal and external pumping gears rotated 30 by and having an axial movement with said rotor, a spring adapted to force the rotor and gears toward the front of the pumping chamber, means for conducting discharge pressure to the back of the rotor for, with 35 said spring, forcing the rotor and gears toward the front of the pumping chamber, and means on the intake side permitting an unrestricted flow of fluid to the front of the pumping chamber but preventing the escape 40 of fluid back from the pumping chamber so as to keep the fluid pressure on the front of the rotor substantially the same as the fluid pressure on the back of the rotor when the compressor is idle and thereby lower the 45 starting torque of the compressor.

8. A rotary compressor comprising a casting containing a pumping chamber with an intake to and a discharge from said chamber, a rotor rotatable in and having an axial 50 movement in said chamber, intermeshing internal and external pumping gears rotated by and having an axial movement with said rotor, said gears being located on the front

50 of the rotor, means for conducting discharge pressure against the back of the rotor for forcing the gears toward the front end of the pumping chamber, and means on the intake side permitting an unrestricted flow of fluid to the pumping chamber but preventing the escape of fluid back from the pumping 55 chamber so as to keep the pressure on the front for the rotor substantially the same as on the back of the rotor when the compressor is idle and thereby lower the starting torque of the compressor. 70

9. A rotary compressor comprising a casting containing a pumping chamber with an intake to and a discharge from said chamber, intermeshing internal and external pumping gears rotated in and having an 75 axial movement in said chamber, means for applying spring pressure and discharge pressure to the back of the gears for forcing the gears toward the front end of the pumping chamber, and means on the intake side 80 permitting an unrestricted flow of fluid to the front of the pumping chamber but preventing the escape of fluid back from the pumping chamber so as to keep the fluid pressure on the front of the gears substantially 85 the same as the discharge pressure on the back of the gears when the compressor is idle and thereby lower the starting torque of the compressor.

10. A rotary compressor comprising a casting containing a pumping chamber with an intake to and a discharge from said chamber and a cavity communicating with the back of said chamber, a rotor rotatable in and having an axial movement in said chamber, 90 said rotor having a passage from back to front, intermeshing internal and external pumping gears rotated by and having an axial movement with said rotor, a spring in said cavity adapted to force the rotor and gears toward the front of the pumping chamber, means for conducting discharge pressure to the back of the rotor for, with 95 said spring, forcing the rotor and gears toward the front of the pumping chamber, and means on the intake side permitting an unrestricted flow of fluid to the front of the pumping chamber but preventing the escape 100 of fluid back from the pumping chamber so as to keep the fluid pressure on the front of the rotor substantially the same as the fluid pressure on the back of the rotor when the compressor is idle and thereby lower the starting torque of the compressor. 105
